UNITED STATES PATENT OFFICE.

WILLETT M. RAYNOR, OF NEW YORK, N. Y.

LOOSE-LEAF BINDER.

No. 851,693.

Specification of Letters Patent.

Patented April 30, 1907.

Application filed July 19, 1906. Serial No. 326,929.

To all whom it may concern:

Be it known that I, WILLETT M. RAYNOR, of the city, county, and State of New York, have invented a new and Improved Loose-
5 Leaf Binder, of which the following is a full, clear, and exact description.

My invention relates to improvements in loose leaf binders, such as are used for book-keeping purposes, and which are usually in 10 ledger form, but so far as my invention is concerned, the leaves may be for any purpose whatever. This loose leaf construction is being quite generally adopted and an objection to most of them is that the adjusting 15 rods which regulate the thickness of the book and support the perforated leaves project through the book and are likely to scratch the desk on which the book lies; moreover, they render the book awkward to manage.

20 The object of my invention is to obviate this difficulty and produce a simple and inexpensive structure which is adopted to carry the loose leaves either in small or large quantities, and which has adjustable posts adapted 25 to carry the leaves and contained wholly within the binding clips and covers of the book.

With these ends in view, my invention consists of certain features of construction and 30 combination of parts which will be herein-after described and claimed.

Reference is to be had to the accompanying drawings forming a part of this specification, in which similar letters and figures of reference indicate corresponding parts in all the 35 views.

Figure 1 is a broken end view of a book showing my improvements. Fig. 2 is a plan view of one of the binding clips. Fig. 3 is an 40 edge view of the clip shown in Fig. 2. Fig. 4 is an edge view partly in section of the two clips ready for use and spaced apart, and Fig. 5 is a bottom view of the binding clip shown in Fig. 2.

45 The binding clips 10 and 11 can be of any usual construction and as shown the clip 10 is in cross section of a general U shape, the open edge being on the inner side and the clip 11 is merely a flat plate. The two parts 50 of the clip 10 are connected near the ends of the clip by split posts 12 and a locking spring 13 is arranged between posts and bears against them, which locking spring is ad-

justed by a screw 14 journaled in the clip and 55 engaging the spring 13. By tightening the screw the posts 12 are forced against the inner posts 15 and 16 to be presently referred to, and the opposed clips may be fastened in relation to each other.

The leaf posts comprise the parts 15 and 16, the post 15 being fixed to the plate 11 and having threaded and socketed upper ends which receive the reduced and threaded parts 16^a of the post sections 16. These in turn may be socketed as shown so that the 65 posts can be extended to any necessary length. The upper ends of the post, or at least, the ends opposite the part 15 (they may be either upper or lower, for that matter) enter the split posts 12, as above stated. 70 The split posts merely guide the parts 16 which can be built up to any necessary extent.

The book is provided with any usual form of cover, as, for instance, the kind shown in 75 Fig. 1, where the covers 17 and 19 are provided with canvas or leather surfaces, and the cover preferably connects by the webs 18 with the clips 10 and 11, the material of the cover being wrapped around and pasted, 80 or otherwise fastened to the clips. This, however, is not essential, and any suitable cover can be used without affecting the principle of my invention.

It will be seen that the structure which I 85 have shown provides a book which is perfectly smooth on both sides, and which can lie flat upon the desk without injuring the latter, and that the structure can be built up easily, and the built up leaf holding posts 15 90 and 16 extended to any necessary length, so as to form a book of any thickness.

Having thus fully described my invention, I claim as new and desire to secure by Letters Patent,—

1. A structure such as described comprising opposed cover clips, split posts carried by one of the clips sectional posts connecting the clips, certain of said posts engaging the split posts and resilient means for forcing the split posts in engagement with the second named posts.

2. A structure such as described comprising opposed cover clips, split posts carried by one of the clips, sectional posts connecting the clips, certain of said posts engaging

the split posts and a spring for forcing the split posts in engagement with the second named posts.

3. A structure such as described comprising opposed cover clips, split posts carried by one of the clips sectional posts connecting the clips, certain of said posts engaging the split posts, a spring for forcing the split posts

in engagement with the second named posts, and means for adjusting the tension of the spring.

WILLETT M. RAYNOR.
